United States Patent

Des. 241,238
Patented Aug. 31, 1976

241,238

WATCH CROWN

Raymond J. Grohoski, Watertown, Conn., assignor to
Timex Corporation, Waterbury, Conn.

Filed Oct. 16, 1974, Ser. No. 511,131

Term of patent 14 years

Int. Cl. D10—07

U.S. Cl. D10—131

FIG.1

FIG. 2

FIG. 3

FIG. 4

FIG. 1 is a perspective view of a watch crown showing my new design;

FIG. 2 is a top plan view thereof;

FIG. 3 is an outer side elevational view thereof, the inner side being plain and unornamented;

FIG. 4 is a bottom plan view thereof.

I claim:

The ornamental design for a watch crown, as shown.
